UNITED STATES PATENT OFFICE

131,453

DESIGN FOR A REVOLVING COUNTER

John V. Avila, San Jose, Calif.

Application August 13, 1941, Serial No. 102,824

Term of patent 7 years

To all whom it may concern:

Be it known that I, John V. Avila, a citizen of the United States of America, residing at San Jose, county of Santa Clara, and State of California, have invented a new, original, and ornamental Design for a Revolving Counter, of which the following is a specification, reference being had to the accompanying drawing, forming a part thereof, wherein the figure is a perspective view of a revolving counter, showing my new design.

I claim:

The ornamental design for a revolving counter, as shown.

JOHN V. AVILA.
